UNITED STATES PATENT OFFICE.

CHARLES T. STEPHENS, OF CHICAGO HEIGHTS, ILLINOIS, ASSIGNOR TO GEORGE S. ANGUS, OF CHICAGO HEIGHTS, ILLINOIS.

STRIKER DEVICE FOR PLAYER PIANOS.

Application filed February 2, 1925. Serial No. 6,382.

This invention relates to a striking device for player pianos and has for its primary object the construction of a striking device of two parts readily disconnected allowing 5 ready access to the air chamber.

An object of the invention is the construction of the arm, frame and diaphragm together as a unit to be readily connected or disconnected from the air chamber structure. 10 A feature of my invention is the novel manner of associating and connecting the removable parts so that they will always assume an accurate position when arranged in place.

15 Besides the above my invention is distinguished in the simplicity of construction.

With these and other objects in view the invention will be better understood from the following description taken in connection 20 with the accompanying drawing, wherein:

Fig. 1 is a top plan view of the device.

Fig. 2 is a sectional view on the line 2—2 of Fig. 1.

25 Fig. 3 is a sectional view on the line 3—3 of Fig. 1.

Fig. 4 is an enlarged sectional view with parts separated.

Again referring to the drawing illustrating one of the many constructions of my invention, the numeral 1 designates the supporting structure shown in this particular case as a casing 2 having the side wall 3 and bottom 4 provided with a hole 5 for communication with the well-known pneumatic elements. It will be noted that the top of the casing is open over which extends a diaphragm 6 having the required flexibility with the marginal edge portion sealed in any suitable manner to the frame 7. In securing the 40 diaphragm to the frame the clamp 8 may also be used.

Struck from the frame is a tongue 9 received in a hole 10 formed in the striker arm 11 to pivot the arm to the frame. One end 45 of the arm is rigidly attached to the diaphragm as is indicated at 12. Thus, it will be seen that the arm, diaphragm and frame are connected together as a unit in a very accurate manner and these parts may be 50 readily connected or disconnected from the casing so that ready access may be had to the air chamber, or a new unit substituted.

The accuracy with which the parts may be assembled and the simple substantial manner 55 in which the parts are connected is a very

important feature of my invention, and when taken in conjunction with the many other advantages of the structure provides a meritorious invention and, therefore, I do not desire to be limited in any manner except as 60 set forth in the following claims.

It will be noted that the device shown consists of a tapered casing or air box 2 which gradually decreases in depth from one end to the other. The bottom of each box is attached to its associated player action by screws as shown here so it can be easily removed. The casing or box is provided with a removable top which carries the flexible diaphragm 6. The body of the box and the 65 top are preferably made of metal and will therefore last for many years. Since the diaphragm is not provided with folds as in the ordinary striker action, it will last for many years. If, for example, in transporting the device or for any other reason a diaphragm should be injured, it is only necessary to send for another top from the factory and any one can remove the top having the 70 injured diaphragm and place the new top in 75 position.

Having thus described my invention, what I claim is:

1. A striker device for player pianos comprising a tapered casing deeper at one end 80 than at the other separate from the pneumatic element and open at the top, said casing adapted to be fastened to the pneumatic element and provided in its bottom with an opening which communicates therewith, a 85 cover for said casing having an opening therethrough, a flexible diaphragm confined at its edges by said cover so as to close said opening, and a striker arm projecting part way across the opening in the cover and attached to said diaphragm.

2. A striker device for player pianos comprising a casing separate from the pneumatic element and open at the top, said casing adapted to be fastened to the pneumatic element and provided in its bottom with an opening which communicates therewith, a cover for said casing having an opening therethrough, a flexible diaphragm confined at its edges by said cover so as to close said opening, and a striker arm projecting part way across the opening in the cover and attached to said diaphragm, a projection on said cover extending through a hole in said striker arm and which acts as a pivotal point 100 105 110

for the striker arm, so that when the dia-
phragm is moved the striker arm will be
rocked about said pivotal point.

3. A striker device for player pianos com-
prising a tapered casing gradually decreasing
in depth from one end toward the other,
separate from the pneumatic element and
open at the top, said casing adapted to be
fastened to the pneumatic element and pro-
vided in its bottom with an opening which
communicates therewith, a removable cover
for said casing having an opening there-
through, a flexible diaphragm confined at its
edges by said cover so as to close said opening,
and a striker arm projecting part way across
the opening in the cover and attached to said
diaphragm.

4. A striker device for player pianos com-
prising a tapered casing gradually increasing

in depth from one end to the other and sepa-
rate from the pneumatic element and open at
the top, said casing adapted to be fastened to
the pneumatic element and being provided
in its bottom with an opening which communi-
cates therewith, a cover for said casing
having an opening therethrough, a flexible
diaphragm confined at its edges by said cover
so as to close said opening, a striker arm pro-
jecting from the shallow end of the casing
across said opening toward the deeper end of
the casing and directly fastened to said dia-
phragm beyond the middle portion of the
casing so that the throw of the diaphragm
due to movement of the striker arm is in the
deeper end of the casing.

35 In testimony whereof I affix my signature.

CHARLES T. STEPHENS.
